(57) **CLAIM**

The ornamental design for a headphone stand, as shown and described.

DESCRIPTION

FIG. 1 is a front, left and top perspective view of a headphone stand, showing my new design;
FIG. 2 is a rear, right and bottom perspective view thereof;
FIG. 3 is a front view thereof;

FIG. 4 is a rear view thereof;
FIG. 5 is a left side view thereof;
FIG. 6 is a right side view thereof;
FIG. 7 is a top plan view thereof;
FIG. 8 is a bottom plan view thereof; and,
FIG. 9 is a perspective view in use thereof.

The broken lines shown in the drawings illustrate portions of the headphone stand that form no part of the claimed design.

1 Claim, 9 Drawing Sheets
